UNITED STATES PATENT OFFICE.

HARRY NAJARIAN AND WALTER V. NAJARIAN, OF NEW YORK, N. Y.

PLUCKING DEVICE.

Application filed May 14, 1928. Serial No. 277,565.

This invention relates to devices for renovating carpets and rugs, dermatological purposes and other like uses. More particularly the invention is directed to an instrument 5 for removing threads that mar the appearance of washed carpetings such as, the so called "Oriental" rugs and as a depilatory, as for example, for plucking the hairs to shape eyebrows in personal beautifying 10 treatments.

One object of the invention is to provide a power-driven device of the character described which is easily manipulated by an operator to quickly remove an anchored 15 thread or hair without injuring adjacent structures.

Another object of the invention is to provide, in an improved device of the character described, an attachment of simplified 20 construction for engaging with on contact and removing an anchored thread or hair, said instrument being adapted to be driven through a flexible power transmission.

A further object of the invention is to 25 provide an improved device of the character described comprising a few and simple parts forming a compact instrument, which shall be easy to operate, cheap to manufacture, and practical and efficient to a high degree 30 in use.

Other objects of this invention will in part be obvious and in part hereinafter pointed out.

The invention accordingly consists in the 35 features of combinations of elements and arrangement of parts which will be exemplified in the constructions hereinafter described and of which the scope of application will be indicated in the following 40 claims.

In the accompanying drawing, in which is shown various possible embodiments of this invention.

Fig. 1 is a perspective view showing the 45 improved device embodying the invention being applied to remove undesirable threads showing in the pattern of a washed "Oriental" rug.

Fig. 2 is an elevational view of the 50 improved thread engaging attachment terminating the flexible power shaft of the device.

Fig. 3 is an enlarged cross-sectional view taken on lines 3—3 in Fig. 2.

Fig. 4 is an enlarged elevational fragmentary view, partly in sections, showing

a modified form of the attachment adapted to be used for dermatological purposes; and

Fig. 5 is a perspective view of a modified form of member having a pointed end shaped to facilitate separating out the undesirable cotton threads and guiding the latter for plucking. 60

Oriental carpeting, such as "Chinese" rugs, are usually dyed their finished color after being woven, and any cotton threads 65 or ends extending to the visible nap surfaces of the rugs are rendered inconspicuous because they take practically the same color as the wool nap forming the wearing surfaces. But as such rugs are subjected 70 only to processes for fixing the dye colors on woolen materials forming the nap surfaces to make the colors fast, said rugs when laundered or cleansed have the color of the cotton materials entirely washed out or faded so as to leave the nap surfaces spotted by the cotton threads. It is therefore necessary to pluck out said cotton threads to 75 avoid marring the appearance of the rugs.

In order to quickly and easily remove 80 these undesirable threads an improved device 10 embodying the invention is provided.

Referring in detail to the drawing, the device 10 is seen to comprise a suitable power means such as an electric motor 11 fitted 85 with a flexible drive transmission 12 which is terminated by an attachment holder 13. Said motor, transmission and holder may be of any well known construction, as for example such as employed for dental work. 90 The transmission 12 is here seen to comprise an elongated tubular shielding casing 12^a through which the coil wound drive-shaft 12^b extends, and the holder 13, which includes a finger grip housing 13^a terminating 95 said casing 12^a and enclosing a slide clutch 13^b mounted to revolve with said shaft 12^b. The holder 13 by means of said clutch is adapted to releasably engage various tools, such as a twist drill 16, to be rotated by the 100 motor 11 through the transmission 12 in the well understood manner.

An attachment denoted generally at A is provided for removing an undesirable thread T of a rug R as will hereinafter more fully appear. Said attachment A may be made integral with the housing 13^a or may form 105 separate structures including a connecting piece 14 and member 15 mounted to extend from said housing as shown in Figs. 2 and 3. 110

The connecting piece 14 has a sleeve portion 14^a firmly secured to the end of the housing 13^a, and a saddle portion 14^b projecting from said sleeve portion 14^a. The 5 saddle portion 14^b may be formed with passage openings 14^c to give access to the portion of the drill 16 in the holder 13 adjacent to the clutch 13^b, and a mounting end 14^d on which the member 15 is adjustably secured. The member 15 may form a conical shell structure through which extends the twist drill 16, said member being provided with an opening 15^a extending down from the apex 15^b for exposing only an end portion 16^a of said drill. The extreme outer 10 portion of the rim of said opening 15^a is preferably made to align with the axis X—X of rotation of the drill or permitting the fluted spiral grooves 16^c at said drill end 15^b to engage on contact with said threads T. A thread T caught in a groove 16^c of the revolving drill and carried against the relatively fixed rim edge 15^c of said 15 opening causes the thread to be plucked out and removed from the rug. As seen from 20 Figs. 2 and 3, the member 15 also serves as a shield, to guard the operation and rug against accidental injury, the apex 15^b of said member partially covering the sharp 25 end 16^b of the drill and forming a guarding closure to prevent the drill end from accidentally injuring the rug structure during the thread removing operation. The apex 30 15^b also provides a convenient means for 35 resting the attachment against a supporting surface.

To provide for various lengths of drills, the member 15 has a threaded base 15^d which screws into the mounting end 14^d of the connecting piece 14 and is secured in set position by the locknut 17.

In using the invention, the device 10 is assembled as shown in the drawing and the motor is connected to a suitable electrical 40 power source (not shown). The operator 45 simply grasps the holder like a pencil and manipulates the attachment A to bring the exposed portion 16^a of the drill in contact with an undesired cotton thread T showing 50 in the nap surface of the rug R, as is clearly illustrated in Fig. 1. The thread is engaged in the revolving spiral flutes 16^c of the drill 16, plucked out and expelled through the 55 passage openings 14^c of the saddle portion 14^b, the relatively fluffy woolen tufts of the nap surface adjacent the threads T being left unaffected.

In Fig. 4 is shown an enlarged end of a modified form of attachment adapted to be 60 used for dermatological purposes such as plucking hairs in shaping eyebrows and as a depilatory. Here the member 115 and drill 116 have all edges smoothly rounded to prevent accidental injury to the tissues surrounding the hairs when applying the device 65

to the person's body. Another modified form of shielding member embodying the invention is shown at 215 in Fig. 5. Here the apex 215^b is extended and chamfered as at 215^d and 215^e to provide a pointed end 70 or finger 215 which facilitates manipulating the separation of the undesirable cotton thread from the wool nap and aids in directing said thread to the drill end for plucking. 75

It will thus be seen that there is provided a device in which the several objects of this invention are achieved and which is well adapted to meet the conditions of practical use. 80

As various possible embodiments might be made of the above invention, and as various changes might be made in the embodiments above set forth, it is to be understood that all matters herein set forth or shown 85 in the accompanying drawing are to be interpreted as illustrative and not in a limiting sense.

Having thus described our invention, we claim as new and desire to secure by Letters-Patent: 90

1. A machine of the character described comprising in combination, a flexible rotatable transmission, and a hand device having a single member revolvable with said transmission for engaging on contact and plucking one of several closely spaced threads or hairs. 95

2. In a machine of the character described, a hand-manipulated device including a fluted revolvable member for engaging on contact and plucking one of a group of closely spaced threads or hairs. 100

3. A device of the character described comprising means for engaging and plucking one of a group of closely spaced threads or hairs on contact therewith including a revolvable member, and a relatively fixed member having means through which said revolvable member extends. 105

4. A hand-manipulated device of the character described comprising a shell member having an opening, a member revolvably mounted within said shell member having a portion thereof exposed at said opening for engaging and plucking an individual thread or hair presented at said opening. 115

5. A device of the character described comprising hand-manipulated power driven means for selectively engaging and plucking a thread or hair from a closely spaced group on contact therewith including a revolvable member, and guiding means communicating with said first mentioned means for expelling said thread or hair from the device. 120

6. A machine of the character described comprising a rotatable transmission, and a hand-manipulated device having a single member revolvable by said transmission and a shell structure extending about said mem- 130

ber, said structure having an opening to expose a portion of said member whereat an individual thread or hair is engaged and plucked on contact with said portion.

- 5 7. A machine of the character described comprising a rotatable transmission, a hand-manipulated holder terminating said transmission, a device mounted on said holder, said device having a single member revolv-
 10 able by said transmission, and a shell structure surrounding said member having an opening adapted to pluck an individual thread or hair on contact therewith, said device having a passage opening spaced from
 15 said structure opening wherethrough the plucked material is expelled.

8. In a machine of the character described, a hand-manipulated holder, a device extending from said holder comprising a revolv-
 20 able member, a shell structure extending about said member, a connecting piece for supporting the structure from said holder, said structure having an opening to expose one portion of said member adapted to pluck
 25 on contact with said portion an individual thread or hair, said piece having a passage communicating with the interior of said structure wherethrough the plucked material is expelled.

- 30 9. A machine of the character described comprising a rotatable transmission, and a hand-manipulated device having a single member revolvable by said transmission, a shell structure extending about said member adapted to engage and pluck a thread or hair on contact with said portion, and means for adjustably mounting said structure with respect to said member to accommodate members of various sizes.

- 40 10. In a hand-manipulated device of the character described, a shell member and fluted means rotatably mounted within said member for plucking individual hairs or threads contacting with said means.

- 45 11. In a hand-manipulated device of the character described, a shell member and fluted means rotatably mounted within said

member, said member having an opening adjacent one end of said means whereat a thread or hair may be brought in contact 50 with said means for plucking.

12. In a hand-manipulated device of the character described, a shell member, and revolvable means coacting with said member for plucking a hair a thread on contact 55 with said means, said member having a pointed portion to facilitate guiding the device in the plucking operation.

13. In a hand-manipulated device of the character described for plucking a nap material, a shell structure, and a member revolvably mounted to extend through said structure for plucking an individual hair or thread of said nap material brought in contact with said member, said structure having means extending therefrom to facilitate separating out the hair or thread to be plucked from the nap material. 60 65

14. In a hand-manipulated device of the character described, a shell structure, and a fluted member revolvably mounted in said structure, said structure having an opening adjacent the end thereof for exposing a portion of said member to permit contact a hair a thread with said portion for plucking, 70 said structure terminating in a pointed extension to facilitate selecting and guiding the materials to be plucked to the opening. 75

15. A portable device of the character described comprising a hand tool having revolvable means for selectively applying to any one of a group of closely spaced threads or hairs for individually plucking the latter. 80

16. A portable device of the character described comprising a hand tool including 85 an elongated revolvable member having means at one end for engaging and plucking an individual thread or hair on contact from a nap surface.

In testimony whereof we affix our signatures. 90
